UNITED STATES PATENT OFFICE.

WALTER D. WOOD, OF ALLENTOWN, PENNSYLVANIA, ASSIGNOR TO FUEL SAVING COMPANY, OF ALLENTOWN, PENNSYLVANIA, A CORPORATION OF PENNSYLVANIA.

SLAG-PAN FOR FINE-FUEL BURNERS.

1,234,848.

Specification of Letters Patent. Patented July 31, 1917.

Application filed November 15, 1916. Serial No. 131,377.

To all whom it may concern:

Be it known that I, WALTER D. WOOD, a citizen of the United States, and resident of Allentown, in the county of Lehigh and State of Pennsylvania, have invented certain new and useful Improvements in Slag-Pans for Fine-Fuel Burners, of which the following is a specification, reference being had therein to the accompanying drawing.

10 This invention relates to a dumping receptacle forming an accessory part of a fire box or chamber belonging to a locomotive or boiler furnace, or any other kind of a furnace, in connection with which powdered fuel such as crushed or comminuted coal is used and burned. The primary object of the invention is to provide a simplified and more effectively operative pan or receptacle located beneath the furnace and receiving 15 and disposing of the accumulations of the products of combustion, such for example as the slag resulting from the burning of the powdered fuel and other refuse materials which must be disposed of in order that 20 the fire may not be clogged and combustion may be freely permitted. The invention, therefore, may be said to consist essentially in a slag pan and suitable means for dumping the same, the details of which are hereinafter set forth, and also the invention comprises numerous special features and peculiarities in the leverage for dumping and the other mechanical parts used for the same purpose so that the slag pan or receptacle 25 may be discharged of its contents whenever desired; and the invention also comprises numerous elements of construction, combination and arrangement, substantially as will be hereinafter described and then more 30 particularly pointed out in the claims.

In the accompanying drawing illustrating my invention:

Figure 1 is an end view of my improved slag pan and its dumping mechanism;

45 Fig. 2 is a top plan view;

Fig. 3 is a transverse section;

Fig. 4 is a side elevation.

Similar characters of reference designate corresponding parts throughout the different figures of the drawing.

1 denotes the bottom of a fire box or furnace of a locomotive or other structure with which my improved slag pan is employed. It will be understood that the invention may

have a wide variety of uses where there are 55 slag and other accumulations required to be disposed of either in a locomotive or stationary furnace, or any kind of boiler furnace, or any other place where pulverized fuel is burned and where slag and similar 60 objectionable debris is likely to accumulate as the result of the burning and requires to be taken away in order that the combustion may proceed without clogging.

At some suitable point in the bottom of 65 this furnace or fire box there is an opening, as 2, beneath which my improved slag pan is located. This preferably is made in the form of an oblong or other suitably shaped box or frame 3, having downwardly and outwardly flaring sides 4 secured at their ends to the downwardly and outwardly flaring ends 5, whose bottom edges 6, 6 incline upwardly and outwardly from the central point. It is desirable that the sides 4, 4 and 75 ends 5, 5 should slope outwardly in order that the slag that drops down through the opening 2 may not choke up against these side walls 4, but will fall freely down upon the bottom of the pan. This bottom consists 80 of two doors or leaves 7, 7 which are hinged by hinges 8 to the lower longitudinal edges of the sides 4, and said leaves 7 are adapted to be lifted from the position shown in Fig. 3 where when open they hang vertically 85 upon their hinges 8 to the position shown in Fig. 1 where they close the bottom of the receptacle 3 and have their inner opposite edges in meeting contact with each other, while in their upward movement these 90 leaves 7, 7 come into close contact with the inclined lower edges 6, 6 of the end members 5, which I have already described. When the leaves 7, 7 swing downwardly the pan opens so that its contents will be discharged, but when the leaves 7, 7 are closed, as shown in Fig. 1, they form the bottom of the pan and sustain the weight of any 95 slag or any foreign matter that ensues from the process of combustion and works its way 100 through the opening 2 into the receptacle 3. This pivoting of the upper edges of the leaves or plates 7 is accomplished in any desired manner, but preferably by means of pins or rods 8 carried in suitable bearings 9, 105 secured to the sides 4 and suitable bearings 10 secured to the doors 7, all as clearly indicated in Fig. 4.

At each end of the slag pan there is a pair of links 11 and 12 whose lower ends are suitably pivoted to the ends of the doors 7 and whose upper ends are pivoted to crank arms, the upper end of each link 11 being pivoted to a crank arm 13, and the upper end of each link 12 being pivoted to a crank arm 14. At one end of the pan said crank arms 13 and 14 are connected to bell crank levers 15 and 16, which bell cranks are fast on horizontal parallel longitudinal shafts 17 and 18, while at the other end of the pan the crank arms 13 and 14 are preferably only single crank arms made fast on these shafts 17 and 18, as shown in Fig. 4. The bell crank levers 15 and 16, therefore, not only have the arms 13 and 14 which are pivoted to the links 11 and 12, but also they have the crank arms 19 and 20. At one end 10 of the pan, therefore, there are these bell crank levers having members 19 and 20 projecting toward each other. A link 21 connects the lower end of arm 19 with the upper end of arm 14, as shown in Fig. 1, being pivoted to both of said arms. Also to the end of arm 20 is pivoted a link 22 whose opposite end is pivoted to an arm 23 of a bell crank lever having an operating handle 24, said bell crank lever being pivoted at 25 in a bracket 26 attached to some convenient part 27 of the locomotive frame, the lever handle 24 serving as the dump lever handle to open the doors 7.

The two links 11 and 12 while occupying a generally vertical position are inclined outwardly and are bent or curved so that their upper ends are carried considerably beyond the outer faces of the sides 4 of pan 3. This arrangement makes the leverage 35 self-locking, since the upper ends of links 11 and 12 which are pivoted to the arms 13 and 14 at the opposite ends of the pan are past the line which might be drawn through the centers of the pivots of bell crank levers 15 and 16 and the pivots at the lower ends 40 of links 11 and 12, as shown by the dotted lines *a*, *a*, in Fig. 1. Furthermore it will be perceived that in view of the fact that the lever 24 is pivoted at 25, and that the said 45 lever arm 24 is much longer and consequently considerably heavier than arm 23, said lever 24 is able by its own weight to keep the link 22 in compression and thus prevent or counteract any effect that the 50 vibration of the locomotive or the running of the train might have to cause the doors or leaves 7, 7 to fly open and prematurely discharge the contents.

An additional safety device consists of a 55 steel safety pin 28 which is inserted in the dump lever bracket 26 at a point close to the dump lever 24, as shown in Fig. 1, and when in place it is impossible to lift the lever 24 for the purpose of operating the 60 pan to discharge its contents. It will be

noted also that the links 11 and 12 of which there are two adjacent to each end 3 are prevented from going past their centers of operation any farther than is desirable by reason of the fact that they come in contact with and rest upon the hubs of the bell crank levers 15 and 16. Said bell cranks 15 and 16 have their members separated for this purpose so as to occupy different but parallel planes, and between the arms of each bell crank there is a hub, as shown. Ordinarily the pan will be dumped by removing the safety pin 28 and lifting the lever 24, the result of which through the connection of arm 23 with link 22 will be to draw on said link 22 and thereby vibrate the bell crank 16, which, being connected with the bell crank 15 by the link 21, imparts a simultaneous vibration to bell crank 15 so that the two bell cranks 15 and 16 75 oscillate simultaneously and communicate motion to the links 11 and 12 which are pivoted to said bell cranks and thus open the doors or leaves 7, and as said bell cranks 15 and 16 are fast on the shafts 17 and 18 80 at one end of the pan, motion is communicated to the other end of the pan through these shafts 17 and 18 so that the arms 13 and 14 at said end of the pan are operated at the same time, and the links 11 and 12 85 at that end partake of the same movement as the first-named pair of links, it being evident, therefore, that at both ends of the pan the curved links 11 and 12 operate in the 90 same way and produce similar effects upon the leaves 7, 7. Obviously a reverse movement of the dump lever handle 24 will restore the parts to the former position and close up the doors or leaves 7 and place the 95 pan in the same condition that it was before it was discharged. 100

Although the pan is ordinarily dumped by the operator when he is standing on the ground outside of the frame or at some other point, yet it must be evident under many conditions it may be preferable to operate the dumping mechanism from the engineer's cab, and in order to provide means for this with ease and convenience, I extend one of the longitudinal shafts on which the bell cranks 15 and 16 and the crank arms are 105 mounted, that is to say, one or the other of the shafts 17 or 18 (in the particular example illustrated it is the shaft 18) back to some point beneath the cab say, or to some point where it is connected to other shafts or levers so that the dumping operation may be accomplished from the distant point, that is to say, from a point within the cab. 110

Obviously many changes may be made in 115 the precise construction and arrangement of the various parts of my improved slag pan and its dumping mechanism without exceeding the natural boundaries of the invention 120 herein portrayed, and I, therefore, reserve 125 130

the liberty of making all such changes as may be necessary provided I do not go beyond the proper scope of the claims.

Having thus described my invention, what I claim as new and desire to secure by Letters Patent, is:—

1. In a slag pan for fine fuel burners, the combination with a pan having its sides and ends sloping downwardly and outwardly so that the cross-sectional area of the bottom is larger than the top and a pair of doors hinged to the lower bottom edges of the pan so that when opened they will fall through an arc vertically downward and outward from the bottom of the pan, of a pair of links at each end of the pan pivoted to the doors, said links being bent so as to form a self-locking combination when the doors are closed, crank levers at the ends of the pan pivotally connected to the bent links, means connecting the crank levers so that they will operate in unison, and means for actuating the crank levers in dumping the pan.
2. In a slag pan for fine fuel burners, the combination with the pan having its sides and ends sloping downwardly and outwardly so that the cross-section area of the bottom is larger than the top and a pair of doors hinged to the lower bottom edges of the pan so that when opened they will fall through an arc vertically downward and outward from the bottom of the pan, of a pair of links at each end of the pan pivoted at one end to the doors, said links being bent so as to form a self-locking combination when the doors are closed, crank levers at the ends of the pan pivotally connected to the bent links, the pivotal points at the upper ends of the bent links being laterally beyond the center of revolution of the crank levers and the centers of the lower pivots connecting the bent links with the doors, means connecting the crank levers so that they will operate in unison, and means for actuating the bent links.
3. In a slag pan for fine fuel burners, the combination with the pan having its sides and ends sloping downwardly and outwardly so that the cross-sectional area of the bottom is larger than the top and a pair of doors hinged to the lower bottom edges of the pan so that when opened they will fall through an arc vertically downward and outward from the bottom of the pan, of a pair of links at each end of the pan pivoted at one end to the doors, said links being bent so as to form a self-locking combination when the doors are closed, crank levers at the ends of the pan pivotally connected to the bent links, the pivotal points at the upper ends of the bent levers being laterally beyond the center of revolution of the crank levers and the centers of the lower pivots connecting the bent levers with the doors, means connecting the crank levers so that they will operate in unison, and means for actuating the bent levers.
4. In a slag pan for fine fuel burners, the combination with a pan having its sides and ends sloping downwardly and outwardly so that the cross-sectional area of the bottom is larger than the top, and a pair of doors hinged to the lower bottom edges of the slag pan so that when opened they will fall through an arc vertically downward and outward from the bottom of the pan, pairs of links pivoted at the ends of the pan to the doors, bell cranks mounted at one end of the pan and pivoted to the aforesaid links, the pivotal points thereof being laterally beyond the sides of the pan frame, crank arms at the opposite end of the pan mounted to move in unison with the bell cranks and similarly pivoted to the links at that end, a link connecting the bell cranks together, and operating mechanism pivotally connected to one of the bell cranks whereby the doors may be opened jointly.
5. In a slag pan for fine fuel burners, the combination with a pan having its sides and ends sloping downwardly and outwardly so that the cross-sectional area of the bottom is larger than the top, and a pair of doors hinged to the lower bottom edges of the slag pan so that when opened they will fall through an arc vertically downward and outward from the bottom of the pan, pairs of links pivoted at the ends of the pan to the doors, bell cranks mounted at one end of the pan and pivoted to the aforesaid links, the pivotal points thereof being laterally beyond the sides of the pan frame, cranks at the opposite end of the pan mounted to move in unison with the bell cranks and similarly pivoted to the links at that end, a link connecting the bell cranks together, and operating mechanism pivotally connected to one of the bell cranks whereby the doors may be opened jointly, said operating mechanism including a single operating lever so that one motion thereof will dump both doors.
6. In a slag pan for fine fuel burners, the combination with the pan proper having its sides and ends sloping downwardly and outwardly so that the cross-sectional area of the bottom is larger than the top, and a pair of bottom doors hinged to the lower bottom edges of the pan so that when opened they will fall through an arc vertically downward and outward from the bottom of the pan, of pairs of bent links at each end of the pan pivoted at their lower ends to the doors and curving outwardly at their upper ends, longitudinal shafts at each side of the pan, bell cranks at one end of the

- 4
- pan mounted on said shafts and having their upper arms pivotally connected to the upper ends of the bent links, the latter pivotal points being beyond the centers of the bell 5 cranks and the pivotal centers at the lower ends of the bent links, crank arms at the other end of the pan mounted on the longitudinal shafts and pivoted to the upper ends of the contiguous bent links, a link pivoted 10 to the lower arm of one of the bell cranks and to the upper arm of the other bell crank, a link pivoted to the lower arm of the last-mentioned bell crank, and an operating bell crank handle pivoted to said link.
- 15 7. In a slag pan for fine fuel burners, the combination with the pan proper having its sides and ends sloping downwardly and outwardly so that the cross-sectional area of the bottom is larger than the top and a pair 20 of bottom doors hinged to the lower bottom edges of the pan so that when opened they will fall through an arc vertically downward and outward from the bottom of the pan, of pairs of bent links at each end of the pan 25 pivoted at their lower ends to the doors and curving outwardly at their upper ends, longitudinal shafts at each side of the pan, bell cranks at one end of the pan mounted on said shafts, each bell crank having offset arms and an intermediate hub on which hub the bent links rest when the doors are closed, said 30 bell cranks also having their upper arms pivotally connected to the upper ends of the bent links, the latter pivotal points being beyond the centers of the bell cranks and the pivotal centers at the lower ends of the bent 35 links, crank arms at the other end of the pan mounted on the longitudinal shafts and pivoted to the upper ends of the contiguous bent links, a link pivoted to the lower arm of one of the bell cranks and to the upper 40 arm of the other bell crank, a link pivoted to the lower arm of the last-mentioned bell crank, and an operating bell crank lever having a long arm and a short arm, the short arm being pivoted to the said link and the long arm being located so that when the doors are closed it will tend by its own 45 weight to exert a force on the movable members of the slag pan to keep the same in a closed and locked position, and means for pivotally supporting said operating bell crank.
- 50 10. In a slag pan, the combination with the pan having sloping sides and ends and a pair of doors hinged thereto, of a pair of 55 links at each end of the pan pivoted to the doors and bent so as to form a self-locking combination when the doors are closed, crank levers at the ends of the pan pivotally connected to the bent links, means connecting the crank levers so that they will operate in unison, and means for actuating the crank levers in dumping the pan including an operating bell crank lever having a short 60 arm and a long arm, said operating bell 65 crank pivoted to said link.
- 70 8. In a slag pan for fine fuel burners, the combination with the pan having its ends and sides sloping downwardly and outwardly so that the area of the bottom is 75 larger than the area of the top and having the lower edges of the end members provided with inclined edges, and a pair of doors hinged at the bottom of the pan, of a pair of links at each end of the pan pivoted 80 to the doors, said links being bent to form a self-locking combination when the doors are closed, levers at the ends of the pans pivotally connected to the bent links, means connecting said levers so that they will operate 85 in unison, and means for actuating the said levers in dumping the pan.
- 90 9. In a slag pan for fine fuel burners, the combination with the pan proper having its sides and ends sloping downwardly and outwardly so that the cross-sectional area of the 95 bottom is larger than the top and a pair of bottom doors hinged thereto, of pairs of bent links at each end of the pan pivoted at their lower ends to the doors and curving outwardly at their upper ends, longitudinal shafts at each side of the pan, bell cranks at one end of the pan mounted on said shafts, each bell crank having offset arms and an intermediate hub on which hub the bent links rest when the doors are closed, said 100 bell cranks also having their upper arms pivotally connected to the upper ends of the bent links, the latter pivotal points being beyond the centers of the bell cranks and the pivotal centers at the lower ends of the bent 105 links, crank arms at the other end of the pan mounted on the longitudinal shafts and pivoted to the upper ends of the contiguous bent links, a link pivoted to the lower arm of one of the bell cranks and to the upper 110 arm of the other bell crank, a link pivoted to the lower arm of the last-mentioned bell crank, and an operating bell crank lever having a long arm and a short arm, the short arm being pivoted to the said link and the long arm being located so that when the doors are closed it will tend by its own weight to exert a force on the movable members of the slag pan to keep the same in a closed and locked position, and means for pivotally supporting said operating bell crank.
- 115 10. In a slag pan, the combination with the pan having sloping sides and ends and a pair of doors hinged thereto, of a pair of 120 links at each end of the pan pivoted to the doors and bent so as to form a self-locking combination when the doors are closed, crank levers at the ends of the pan pivotally connected to the bent links, means connecting the crank levers so that they will operate in unison, and means for actuating the crank levers in dumping the pan including an operating bell crank lever having a short 125 arm and a long arm, said operating bell 130 crank lever being hung pivotally so that its operating arm will be in a substantial horizontal position when the doors are closed so as to tend by its own weight to exert a force on the leverage to keep the doors normally in a closed and locked position.
- 135 11. In a slag pan, the combination with the pan having sloping sides and ends and a pair of doors hinged thereto, of a pair of links at each end of the pan pivoted to the doors and bent so as to form a self-locking combination when the doors are closed, crank levers at the ends of the pan pivotally connected to the bent links, means connecting the crank levers so that they will operate in unison, and means for actuating the crank levers in dumping the pan including an operating bell crank lever having a short arm and a long arm, said operating bell crank lever being hung pivotally so that its

operating arm will be in a substantial horizontal position when the doors are closed so as to tend by its own weight to exert a force on the leverage to keep the doors normally 5 in a closed and locked position, together with a safety pin for preventing displacement of said operating lever.

12. In a slag pan for fine fuel burners, the combination with the pan having its 10 ends and sides sloping downwardly and outwardly and a pair of doors hinged thereto, of a pair of links at each end of the pan pivoted to the doors and bent so as to form

a self-locking combination when the doors are closed, a suitable leverage mechanism 15 for operating the bent links in unison, a link connection with said mechanism, an operating bell crank lever for actuating the link and pivoted thereto, and a safety pin for preventing displacement of the operating lever when the dumping doors are closed. 20

In testimony whereof I hereunto affix my signature.

WALTER D. WOOD.
